CLAIM

The ornamental design for a multi-angle cutting jig, substantially as shown and described.

DESCRIPTION

FIG. 1 is a top perspective view of a multi-angle cutting jig showing my new design;

FIG. 2 is a bottom perspective view thereof, showing the multi-angle cutting jig in an open state;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines depicted in FIG. 1 to FIG. 6 represent an adjusting/tightening knob for use with the multi-angle cutting jig according to the claimed design. The broken lines in the drawings illustrate portions of the multi-angle cutting which form no part of the claimed design.
